UNITED STATES PATENT OFFICE.

HENRY T. HOLLAND, OF NEW YORK, N. Y.

BRACKET.

No. 849,398.

Specification of Letters Patent.

Patented April 9, 1907.

Application filed July 13, 1906. Serial No. 326,099.

To all whom it may concern:

Be it known that I, HENRY T. HOLLAND, a citizen of the United States, residing at New York city, in the county of New York and State of New York, have invented new and useful Improvements in Brackets, of which the following is a specification.

This invention is a bracket adapted to be attached to a wall or the like, and particularly suitable and useful as a support for gas-meters and other similar objects.

It is characterized by simplicity and cheapness, which are highly desirable in brackets of the kind, and also by novel means for attaching the bracket to the wall.

The invention is illustrated in the accompanying drawings, in which—

Figure 1 is a front view thereof. Fig. 2 is a side elevation thereof. Fig. 3 is a top view thereof. Fig. 4 is a side view of the bracket folded.

The frame of the bracket is preferably made of wire and has an upper V-shaped supporting-piece bent to form two arms 6, which are attached to the wall at their free ends, the apex of the V extending outwardly.

The brace consists of a piece of wire bent to form a pair of arms 7, which are hooked, as at 8, at their upper ends through loops 9, formed by a coil or bend in the arms 6, near the outer end thereof.

The arms 6 are attached to the wall or supporting structure by means of swiveling-disks 10, which have holes 11 to receive the nails or screws by which they are fastened to the wall. The disks are made of thin sheet metal and are provided with holes 12 near the edge, through which the arms 6 extend; the arms being upset at the ends, as at 13, so that the disks will not come off. The disks are free to turn on the arms and can thus be turned around and fastened at any angle with respect to the arms, so that the attaching nail or screw will be sure to hit a lath in a plastered wall.

The lower end of the braces 7 is attached to the wall by a disk 14, made similarly of sheet metal, provided with a hole 15 to receive the attaching nail or screw. This disk is connected to the brace at the bend thereof by means of a tongue 16, which is looped around the wire of the brace. Said disk 14 may thus be turned up or down for attachment to the wall.

The device is capable of adjustment or alteration of shape to a certain extent. Thus

the flexibility of the wire allows the arms 6 to be spread so as to make the bracket of greater width and less projection, or they can be brought together with the opposite result. The device is thus capable of use in close quarters or narrow spaces where an inflexible bracket could not be accommodated. By spreading the arms until they stand at a right angle an efficient corner-bracket for a square corner is produced, one arm being attached to each wall and the brace being attached at the corner. For other angles or situations other necessary adjustments may be made. Furthermore, an improved feature of the device is that the brackets can be folded to a small space for transportation or storage. The hinge connection at 9 allows the braces 7 to be swung up to substantially the same plane as the arms 6, so that the devices may be packed and carried flat. The devices have but little weight, but are nevertheless sufficiently strong, even when made of light wire, to support a gas-meter or the like. For heavier work heavier wire can be used, or the brackets may be made of heavier metal bars.

I claim—

1. A bracket comprising a supporting-arm, a brace, and a fastening device at the end of the arm rotatable around the same.

2. A bracket comprising a supporting-arm, a brace, and a fastening for the arm consisting of a disk connected to the arm and which may be turned around the same as an axis.

3. A wall-fastening for a bracket, comprising a sheet-metal disk having a hole near its edge through which the arm of the bracket extends, so that the disk may be turned around the arm.

4. A bracket comprising a supporting-arm, a brace, and a fastener consisting of a sheet-metal disk having a hole near its edge through which the arm extends loosely, the end of the arm being upset behind the disk.

5. A bracket comprising a pair of spaced arms flexibly connected at their front ends and having fastening devices at their rear ends, and a brace hinged to the arms at its upper end and having a fastening device at its lower end.

6. A bracket comprising a piece of wire bent to form a pair of supporting-arms located beside each other and having fastening devices at their ends, and another piece of wire bent to form a brace for both arms and hinged at its upper end to the arms and pro-

vided with a fastening device at its lower end.

7. A bracket comprising a piece of wire bent to form a pair of supporting-arms extending at an angle to each other and adjustable by bending to vary the angle, and a brace comprising a piece of wire bent to form two branches each of which is hinged at the end to one of the arms.

10 8. A folding bracket comprising a piece of wire bent to form a pair of spaced supporting-arms and a loop in each arm, and a piece of wire bent to form a brace for both arms, the ends of said piece being hooked into the 15 loops.

9. A bracket comprising a piece of wire bent to form a pair of supporting-arms and having swiveling-disks at their ends, and a piece of wire bent to form a brace for both arms and hinged at its upper ends to said 20 arms and having a hinged disk at its lower end.

In testimony whereof I have signed my name to this specification in the presence of two subscribing witnesses.

HENRY T. HOLLAND.
